UNITED STATES PATENT OFFICE.

CARL C. GILDNER, OF LOS ANGELES, CALIFORNIA.

DESIGN FOR A FINGER-RING, BROOCH, OR SIMILAR ARTICLE OF JEWELRY.

52,314.

Specification for Design.

Patented Aug. 27, 1918.

Application filed February 7, 1918. Serial No. 215,909. Term of patent 3½ years.

To all whom it may concern:

Be it known that I, CARL C. GILDNER, a citizen of the United States, residing at Los Angeles, in the county of Los Angeles and State of California, have invented a new, original, and ornamental Design for a Finger-Ring, Brooch, or Similar Article of Jewelry, of which the following is a specification, reference being had to the accompanying drawing, forming part thereof.

The figure is a face view of my ring, brooch, or similar article of jewelry.

I claim:

The ornamental design for a finger ring, brooch, or similar article of jewelry, as shown.

CARL C. GILDNER.

Witnesses:

EDMUND A. STRAUSE,
W.M. M. RHEEM.
